HYDRAULIC SERVICE JACK

Edward H. Schultz, Milwaukee, Wis.

Application January 19, 1948, Serial No. 3,047

7 Claims. (Cl. 254—10)

1

This invention relates to improvements in hydraulic service jacks.

It is a general object of the present invention to provide an hydraulic service jack having a novel leverage arrangement, which is so designed that the saddle supporting and lifting members swing upwardly in a manner similar to the boom on a power shovel or crane, stresses in said lifting members being taken in compression and tension to produce maximum strength in proportion to the weight of the structural parts.

A further object of the invention is to provide a jack as above described, wherein the leverage arrangement makes it possible for the jack to handle its full rated capacity at any point in the range of movement thereof. This is to be distinguished from the conventional jack which can handle only about half of its rated capacity in its low position, and which does not reach its rated capacity until near the middle of its lifting range.

A further object of the invention is to provide an hydraulic service jack which is portable and easy to handle, but nevertheless sturdy enough to lift objects up to two tons if required. Due to its compact size, it is small enough to be accommodated in the trunk of a passenger car, a convenience to garages rendering road service.

A further object of the invention is to provide an hydraulic jack wherein the hydraulic pressure in the system is practically uniform throughout the lifting range. Thus, a safety valve for automatically by-passing hydraulic fluid to the reservoir when an overload is applied is rendered accurate throughout the range of lifting movement. In the conventional jack where the hydraulic pressure varies, safety valves are not accurate and therefore additional bulb must be employed in the jacks.

A more specific object of the invention is to provide jacks wherein the hydraulic ram swings with the lifting levers and saddle during raising and lowering movement to make it possible to secure the advantages above described.

A further object of the invention is to provide a lifting jack wherein the operator may select any one of three lifting speeds, the manual effort required being directly proportional to the lifting speed selected. Thus, the operator may select a speed to suit his particular preference. For example, a boy may require the use of a slower speed because of the lower amount of effort necessitated, whereas, a man may prefer to do the same job faster.

A further, more specific object of the invention is to provide a construction as above de-

2

scribed, wherein the selection of pumping speeds is accomplished by a slight rotation of the operating handle in one direction or the other.

A further object of the invention is to provide a jack as above described, wherein the pump has increased efficiency to render relatively short strokes of the handle effective in raising the saddle. Thus, it is possible to use the jack efficiently under low vehicles.

10 A further object of the invention is to provide an improved hydraulic jack wherein the hydraulic pressure release is rendered relatively simple by placing such release under the control of the handle rotation, and wherein the release valve is arranged to close automatically whenever the handle is raised.

Other objects of the invention are to provide an hydraulic service jack which resists wear and therefore has long lasting efficiency, which is relatively simple and inexpensive to manufacture, which is neat in appearance, and which is otherwise well adapted for the purpose described.

With the above and other objects in view, the invention consists of the improved hydraulic service jack, and all its parts and combinations, as set forth in the claims, and all equivalents thereof.

In the accompanying drawing, illustrating one complete embodiment of the preferred form of the invention, in which the same reference numerals designate the same parts in all of the views:

Fig. 1 is a perspective view of the jack showing the saddle in elevated position, part of the handle being broken away;

Fig. 2 is a vertical longitudinal sectional view of the improved jack with the saddle in lowered position;

Fig. 3 is a top view of the jack in collapsed position, parts being broken away, and other parts being broken away and shown in horizontal section;

Fig. 4 is a perspective view of the back end of the jack to show the speed selector arrangement;

Fig. 5 is a fragmentary plan view looking down on the back end of the jack, the handle being removed and parts being broken away and shown in section; and

Fig. 6 is an end elevational view looking at the opposite end of the jack from the end shown in Fig. 5, with parts broken away and shown in vertical section.

The frame and pump mechanism

55 Referring more particularly to the drawings, there are side plates 10 which are spaced apart

to accommodate the operating mechanism. Extending transversely of the plates at the forward end thereof is a front axle 11 and rotatably mounted on the ends of the axle are front wheels 12. At the opposite end the plates are maintained in spaced condition by a pump piston retaining bar 13, and projecting laterally from the outer sides of the plates 10 at said end are brackets 14 to which casters 15 are pivoted on bolts 16, the casters being equipped with caster wheels 17.

Secured between the spaced plates 10 at the rear end of the frame is a pump body 18, the latter including a removable cover 19. Within the upper portion of the pump body is a main reservoir 20 (see Fig. 2) which is in communication with side reservoir portions 21 (see Fig. 3).

In the lower solid portion of the pump body 18 are laterally spaced bores 22 and 23, one of said bores, such as the bore 22, being of larger diameter than the other. Slidable in the bores 22 and 23 are pump pistons 24 and 25 respectively which are hollow to accommodate coil springs 26 and 27. The outer end of each piston is closed as is clear from Fig. 3, and is adapted to project externally of the pump body from its bore. The closed end of each piston forms a seat for one end of the coil spring therein, and the other end of the coil spring is adapted to be seated in the inner end of the respective bore 22 or 23. The said inner ends of the bores are interconnected by a transverse duct 28.

Extending between the side reservoir portions 21 is a transversely extending duct 29 which communicates at a point intermediate its length with a vertical duct 30 (see Fig. 2). The upper end of the vertical duct 30 communicates with a larger duct portion 31 so that there is an annular shoulder 32 therebetween forming a seat for a check ball 33. Above the check ball 33 the duct portion 31 is in communication with the passageway 28 connecting the forward ends of the piston bores 22 and 23. Above this point, the duct portion 31 connects with a still larger duct portion 34, there being an annular shoulder 35 formed between said two duct portions and forming a seat for a check ball 36, the latter being located above the passageway 28. The upper end of the duct 34 is adapted to be closed by a removable plug 37.

Extending from one side of the duct 34 and communicating with the inner end of a bore 38 is a short duct 39. The inner end of the bore 38 forms a seat for a relief valve 40. The latter is mounted on the inner end of a stem 41, and the latter projects through a suitable packing 42 to a point outside of the valve body where nuts 43 are threaded thereon. A spring 44 normally urges the relief valve to closing position to prevent the flow of oil from the duct 34 through the duct 39 and passageway 45 into the reservoir 20. The spring tension may be adjusted by means of a nut 46 and is preferably adjusted to permit opening of the valve when pressures exerted thereon exceed 6,800 pounds per square inch.

The hydraulic ram

Leading from the duct portion 34 to a transverse pivot bore 47 in a pivot extension 48 is a duct 49. A forked ram base 50 is connected by a pivot shaft 51 with the extension 48 of the pump body, the ends of the pivot shaft being received in bearings 52 carried by the frame side plates 10. Mounted in the ram base and projecting forwardly therefrom is a ram cylinder 53 within which a piston 54 is movable, there being a ram plunger 55 pro-

jecting from the piston through the forward end of the ram cylinder.

In order to provide for proper communication between the pump and the hydraulic ram, a novel arrangement has been provided which is illustrated more particularly in Fig. 3. The pivot shaft 51 is provided with an annular groove 56 which is so located as to be in communication with the outer end of the oil duct 49, there being suitable oil seals 57 and 58 on each side of the groove 56. A similar annular groove 59 is connected by an obliquely extending internal bore 60 with the annular groove 56, as is clear from Fig. 3. The groove 59 is located in a solid portion of the ram base 50 and there are oil seals 61 on each side of the annular groove 59. The groove 59 in turn communicates with the end of a duct 62 leading into the cylinder 53. It is thus apparent that oil can flow to and from the hydraulic cylinder and that there is no interference as a result of the pivotal mounting for the cylinder and no necessity for employing flexible conduits.

The lifting members and saddle

The outer end of the ram plunger 55 is provided with a head 63 (see Fig. 2) which has a bore through which a transverse shaft 64 extends, the latter having its ends secured in opposite sides of a U-shaped supporting bracket 65 for a saddle 66. Also pivoted on said shaft 64 as at 67 are the outer ends of tie rods 68. The inner ends of said tie rods 68 are pivoted on a shaft 69 which extends transversely between the side plates 10 above the pump body. Another pair of tie rods 70 have their inner ends pivoted on a shaft 71 which extends transversely between the side plates 10 adjacent the pump body. The outer ends of the tie rods 70 are pivoted as at 72 to a shaft 73 which extends transversely of the saddle bracket 65 (see Fig. 6). Connected to the shaft 73 between the pivotal connection 72 by means of a U-strap 74 is one end of each of a pair of coil springs 75. The other ends of the springs are connected to studs 76 projecting from the side plates 10 (see Fig. 3). The tie rods 68 and 70 serve in conjunction with the ram as lifting levers.

The handle control and speed selector

At the rear end of the side plates, and extending transversely thereof, is a handle fulcrum member 77 pivotal on end trunnions 78. The fulcrum member has an intermediately located cylindrical projection 79 formed with a bottom flange 80. A handle member 81 has its lower end inserted into the upper end of a sleeve 82 and secured in position by a bolt 83. Intermediate the length of the sleeve is an internal annular shoulder 84 which is adapted to abut the outer end of the cylindrical extension 79. A flanged retaining ring 85, which coacts with the opposite side of the annular shoulder 84 is connected by a bolt 86 with a cylindrical extension 79. The result of this arrangement is that the handle and lower end sleeve may be rotated on the extension 79, and also the handle may be pumped up and down on the pivot shaft 78.

Projecting from the lower side of the sleeve 82 is a pump operating lever 87 having its lower end in the form of a T as at 88. By referring to Fig. 4, when the handle is in the normal position shown, the T-shaped lower end of the lever 87 will engage both of the pump pistons 24 and 25 to operate said pistons simultaneously. When the handle is rotated a slight distance in one di-

rection around the cylindrical extension 19, the T will contact one of the pistons only, and when it is rotated a slight distance in the opposite direction from the normal position of Fig. 4, it will contact the other piston only. By rotating the handle still further in either direction, levers 89 or 90 (see Fig. 5) may be contacted. These levers are rockably mounted on bolts 91 and 92 to rock between nuts 93 and 94 on one of said bolts, and between nuts 95 and 96 on the other of said bolts. When either of said levers 89 or 90 is rocked to the opposite position from that shown in Fig. 5, it will push outwardly on the nuts 43 which are on the outer end of the relief valve stem 41 and cause opening of said valve to release the oil pressure and allow the oil to flow from the cylinder 53 back into the reservoir 20.

Operation

In use of the jack, if the user desires to raise the jack from the position of Fig. 2 to the position of Fig. 1 at a relatively high rate of speed and does not mind the extra effort required, the handle 81 is rotated in a clockwise direction, referring to Fig. 4, so that the T-shaped end 88 of the lever 87 contacts the end of the piston 24 only. If the operator does not care about the speed but wants to reduce the amount of manual effort required, then the handle 81 is rotated in a counterclockwise direction, referring to Fig. 4, to engage the piston 25 only. If the handle is maintained in the position of Fig. 4, it will engage both pistons simultaneously to give the fastest lifting speed with, however, the greatest amount of manual effort.

With whatever speed is selected the plunger is pumped up and down, which action aided by the springs 26 and 27 which are within the pistons causes the pistons to reciprocate in and out. Referring to Fig. 3, when the spring 27 pushes the piston 25 to the position of said figure, oil is sucked from the reservoir pocket 21 into the ducts 29 and 30. The suction stroke causes the check 33 to be lifted to admit oil into the duct portion 31, duct 28, and piston bore 23. On inward movement of the piston 25 the check ball 33 stays closed and a charge of oil is forced past the check ball 36, and then through the ducts 34, 49, 56, 60, 59 and 62 to the inner end of the ram cylinder 53 to cause an outward push on the ram piston 54. By continued pumping, the ram plunger 55 will be moved outwardly. During such movement the tie rods 68 and 70 pivot on their ends and the saddle is gradually swung upwardly to the position of Fig. 1 against the tension of the springs 75. During such movement stresses are taken both in compression and tension producing the greatest possible strength in proportion to the weight of the structural parts. Also, due to the novel construction, the hydraulic pressure is substantially uniform throughout the range of movement so that the jack is able to raise a full capacity load beginning at lowest starting position of the saddle. During such movement, if any overloading should take place, the relief valve 40 will open to by-pass oil into the reservoir 20. Due to the fact that the hydraulic pressures are uniform throughout the range of movement, the relief valve may be adjusted accurately and proper performance is assured.

To lower the jack it is merely necessary to rotate the handle to a position to contact one or the other of the levers 89 or 90. By pushing downwardly slightly after such rotation, a pull is exerted on the stem 41 of the valve 40 to re-

lease the hydraulic pressure and permit the oil to flow back into the reservoir 20 under the weight of the load, the return also being aided by the spring 75.

Due to the efficiency of the pump design a relatively short stroke of the handle is sufficient to operate the jack. This enables the jack to be used successfully under difficult conditions where the vehicle has a low overhang. The release valve 40, due to the action of the spring 44, closes automatically as soon as the handle 81 is raised or released.

Various changes and modifications may be made without departing from the spirit of the invention, and all of such changes are contemplated, as may come within the scope of the claims.

What I claim is:

1. In an hydraulic jack having a supporting frame and having an elevating saddle, rods pivotally connected between said frame and saddle for swinging movement relative to said frame, an hydraulic ram having a plunger portion pivotally connected to said saddle and having a cylinder portion provided with a base having a pivot bore extending transversely therethrough, an hydraulic pump on said frame having a pivot extension provided with a transverse pivot bore, there being a duct for hydraulic fluid extending from said pump to said bore of said pivot extension and there being a duct extending from the bore of the cylinder base to said cylinder, and a pivot pin supported transversely of the frame and extending through said bores, said pin having fluid ducts therein shaped and positioned to transmit fluid from the pump extension duct to the cylinder base duct in any position of pivotal movement of said cylinder.

2. In an hydraulic jack having a supporting frame and having an elevating saddle, rods pivotally connected between said frame and saddle for swinging movement relative to said frame, an hydraulic ram having a plunger portion pivotally connected to said saddle and having a cylinder portion provided with a base having a pivot bore extending transversely therethrough, an hydraulic pump on said frame, a pivot extension on said frame provided with a transverse pivot bore, there being a duct for hydraulic fluid extending from said pump within said pivot extension to the bore thereof and there being a duct extending from the bore of the cylinder base to said cylinder, and a pivot pin supported transversely of the frame and extending through said pivot bores, said pin having fluid ducts therein shaped and positioned to transmit hydraulic fluid from the duct in the pivot extension on the frame to the cylinder base duct in any position of pivotal movement of said cylinder.

3. In an hydraulic jack having a supporting frame and having an elevating saddle, rods pivotally connected between said frame and saddle for swinging movement relative to said frame, an hydraulic ram having a plunger portion pivotally connected to said saddle and having a cylinder portion provided with a base having a pivot bore extending transversely therethrough, an hydraulic pump on said frame, a pivot extension on said frame provided with a transverse pivot bore, there being a duct for hydraulic fluid extending from said pump within said pivot extension to the bore thereof and there being a duct extending from the bore of the cylinder base to said cylinder, and a pivot pin supported transversely of the frame and extending through said

pivot bores, said pivot pin having an annular groove in registration with the duct of the pivot extension on the frame and having an annular groove in registration with the cylinder base duct and there being an internal duct in said pin connecting said two annular grooves.

4. In an hydraulic jack having a supporting frame and having an elevating saddle, rods pivotally connected between said frame and saddle for swinging movement relative to said frame, an hydraulic ram having a plunger portion pivotally connected to said saddle and having a cylinder portion provided with a base having a pivot bore extending transversely therethrough, an hydraulic pump on said frame, a pivot extension on said frame provided with a transverse pivot bore, there being a duct for hydraulic fluid extending from said pump within said pivot extension to the bore thereof and there being a duct extending from the bore of the cylinder base to said cylinder, and a pivot pin supported transversely of the frame and extending through said pivot bores, said pivot pin having an annular groove in registration with the duct of the pivot extension on the frame and having an annular groove in registration with the cylinder base duct and there being an internal duct extending obliquely through said pin from one side of one annular groove to the opposite side of the other annular groove.

5. In an hydraulic jack: a supporting frame; an hydraulic ram having a cylinder portion provided with a base having a pivot bore extending transversely therethrough; an hydraulic pump on said frame having a pivot extension provided with a transverse pivot bore, there being a duct for hydraulic fluid extending from said pump and in communication with said bore of said pivot extension and there being a duct extending from the bore of the cylinder base to said cylinder; and a pivot pin supported transversely of the frame and extending through said bores, said pin having fluid ducts therein shaped and positioned to transmit fluid from the pump extension duct to the cylinder base duct in any position of pivotal movement of the cylinder.

6. In an hydraulic jack: a supporting frame; an hydraulic ram having a cylinder provided with a cylinder bore and with a base having a trans-

verse pivot bore extending transversely therethrough, there being a passage formed in said cylinder affording communication between the cylinder bore and the transverse pivot bore; an hydraulic pump on said frame having a body formed with a pivot extension provided with a transverse pivot bore, there being a fluid outlet passage formed in said pump body and extending to and in communication with the bore of said pivot extension; and a pivot pin positioned in said cylinder base and pump extension pivot bores, said pin being formed with a passage shaped and positioned to transmit fluid from the pump extension passage to the cylinder base passage in any position of pivotal movement of the cylinder.

7. In an hydraulic jack: a supporting frame; an hydraulic ram having a cylinder provided with a bore and with a projecting end portion; an hydraulic pump carried by said frame, said pump having a body formed with a projecting portion, the projecting portion of said cylinder being pivotally connected to the projecting body portion of said pump, there being a passage formed in said cylinder body communicating with the cylinder bore and extending within the projecting end portion of said cylinder, and there being a fluid outlet passage formed in said pump body and extending within the projecting body portion of said pump; and means including a conduit embodied in said pivotal connection and affording communication between the passages in the projecting portions of said cylinder and pump body for conducting fluid under pressure from said pump to said cylinder bore.
